[57] CLAIM

The ornamental design for a holder for retaining small metallic objects magnetically, as shown and described.

DESCRIPTION

FIG. 1 is a perspective view of a holder for retaining small metallic objects magnetically, showing my new design;

FIG. 2 is a top plan view thereof;

FIG. 3 is a side elevation view thereof, the opposite side being substantially identical;

FIG. 4 is an end view thereof, the opposite end being substantially identical;

FIG. 5 is a bottom plan view thereof;

FIG. 6 is a cross-sectional view taken along line 6—6 of FIG. 2; and

FIG. 7 is a cross-sectional view taken along line 7—7 of FIG. 2.
